UNITED STATES PATENT OFFICE

JOHN W. SANFORD, OF CLAREMONT, NEW HAMPSHIRE, ASSIGNOR TO SULLIVAN MACHINERY COMPANY, A CORPORATION OF MASSACHUSETTS

AUTOMATIC COMPRESSOR CONTROL SYSTEM

Application filed August 10, 1928. Serial No. 298,701.

My invention relates to automatic compressor control systems.

When compressors are driven by electric motors, it becomes important to reduce the cost of power to a minimum. The rate charged by power companies is frequently based on the maximum load demand over a certain interval of time, usually three or four minutes or more. With the unloading mechanism heretofore provided for automatically loading and unloading the compressor in response to variations in demand for compressed fluid the compressor and its driving motor are made to run under full load when the pressure is low and this fully loaded interval may be longer than the interval fixed by the power company as its basis for rates. It is also a fact in many installations that seldom if ever is the full demand placed on the compressor and a common occurrence is a compressor installation of one or more compressors whose capacity is around two hundred percent of the average demand. In this instance, if the compressor is provided with an unloader which will permit full load to be placed on the compressor for a period longer than the maximum demand interval fixed by the power company, it will be seen that the user of compressed air may be forced to pay almost twice the amount for power that would be necessary if the load could be properly distributed. At times, as is frequently the case in compressor installations for mines, the demand for air may be even considerably lower than fifty percent of the capacity of the compressor, but if the compressor and its motor are forced to run under full load over any considerable length of time the cost of power will be practically as great as it would be if the demand for air were around one hundred percent load.

It is therefore the primary object of my invention to provide compressor controlling mechanism which will meet the above conditions and enable the load on the compressor to be controlled so as to keep the cost of power down to a minimum consistent with the demand for air. Another object is to provide improved means for controlling the load on a motor so that the load will not exceed a certain predetermined percentage of full load. A further object is to provide improved means for controlling the load on a compressor so that the average load placed on its driving motor over a certain predetermined small interval of time will not exceed a certain percentage of full load. Still another object is to provide improved means for varying the maximum average load on a compressor over a certain predetermined time interval and to provide means for regulating said time interval. Other objects and advantages of my invention will hereinafter more fully appear.

In the accompanying drawings I have shown for purposes of illustration one form which my invention may assume in practice. In these drawings,—

Fig. 1 is a diagrammatic view in elevation of a compressor system with my improved control mechanism associated therewith.

Fig. 2 is also a diagrammatic view illustrating the various elements of the fluid pressure controlled unloader.

Fig. 3 is a detail sectional view through one of the valves which may be employed in my controlling system.

Fig. 4 is a vertical sectional view through the timing elements of my improved control mechanism.

Fig. 5 is an end elevation of the mechanism illustrated in Fig. 4.

Figs. 6 and 7 are elevation views of the timing mechanism, showing the parts in different positions.

In carrying out my invention I preferably employ the usual elements of an unloading device of the pilot valve controlled type wherein the unloader is moved to unloading position when placed under pressure through operation of the pilot valve. In the line leading from the pilot valve to the unloader in one embodiment of my invention I interpose a special double throw automatic three-way valve from which also leads a connection to the receiver tank independent of the pilot valve. In this latter connection is installed a three-way valve which is capable of permitting air to flow from the receiver tank.

to the first three-way valve or to cut off the receiver tank and vent the line leading to said first three-way valve. The operation of this latter valve is controlled by a special timing mechanism which may assume an almost unlimited number of concrete forms. The operation of the special double throw three-way valve is such that the timing mechanism may put the unloader under pressure independently of the action of the pilot valve and also permit the pilot valve to control pressure to the unloader when the timing mechanism is in position to permit loading.

16 Referring to the specific embodiment of my invention illustrated in the drawings, there is shown in Fig. 1 a compressor of the angle compound type having a low pressure cylinder 1 and a high pressure cylinder 2 with 20 an intercooler 3 interposed between the two cylinders. Compressed fluid is discharged from the high pressure cylinder through a line 4 to a usual receiver tank 5. Since the specific construction of the compressor driving motor does not enter into the present invention, it has not been shown in detail, but a direct connected motor is indicated at 6. The unloader illustrated is of the total closure intake type having a casing 7 to which fluid is supplied directly from the atmosphere or through a suitable pipe 8. Low pressure fluid is supplied from this casing to the compressor through a connection 9 under the control of a double seat valve 10 which is 30 actuated through a stem 11 and piston 12. The valve is normally held in its upper or loaded position by a spring 13 thereby permitting fluid to flow freely to the intake of the compressor. This unloader valve is actuated to closed or unloaded position by fluid pressure acting in the cylinder 14 and the amount of movement is controlled by an adjustable stop 15. For the purpose of controlling pressure in the unloader cylinder 14, my 40 improved control system includes a usual pilot valve mechanism generally indicated 16 which may be of any of the well known types, the one illustrated herein being of the type known as the Penn pilot valve. This 50 pilot valve mechanism operates in a well known manner in response to a predetermined high receiver tank pressure to establish a connection between the receiver tank 5 and the unloader cylinder by way of a line 55 17 leading from the receiver tank through a three-way valve mechanism 18 to the line 19 and thence to the unloader cylinder through a connection 20 under the control of a special three-way valve generally designated 21.

60 When the pressure in the receiver tank reaches a predetermined minimum, the pilot valve mechanism 16 operates the three-way valve 18 to close the line from the receiver tank and vent the line leading from the unloader cylinder. Leading to the special three-

way valve 21 is a third connection 22 which leads to the receiver tank 5 through a three-way valve 23 and a pipe 24.

The construction of the special three-way valve 21 will now be briefly described. A 70 valve element 25 is reciprocably mounted in a cylinder 26 and has conical end portions 27 and 28 which are adapted to close against cooperating seats in the opposite ends of the valve casing to control communication between lines 19 and 22 and the interior of the valve casing. The opposite end flanges 29 and 30 are provided with suitable notches 31 and 32 for establishing free communication between either of lines 19 and 22 and the unloader cylinder through the interior of the valve casing. It will of course be understood that any type of valve may be used in this connection which will operate in a manner substantially similar to the operation of the 80 present valve.

The three-way valve 23 is herein illustrated as being of the same type as that indicated at 18 employed on the Penn pilot valve. The construction of this valve is shown in 90 section in Fig. 3. The valve elements 33 and 34 have conical portions cooperating with conical seats 35 and 36 in the valve casing and are provided with oppositely directed abutting stems 37 and 38. A spring 39 normally 95 tends to hold the valves in their lower position, thus closing valve 34 and opening vent valve 33. Fluid flows freely through the valve casing around the valve stems 37 or 38 to or from the connection 40 which communicates with pipe 22. The valve elements are controlled by means of a movable plunger 41 which is resiliently connected through a spring 42 to the lower valve 33. As shown in Fig. 5, the three-way valve 23 is mounted on a box-like casing 43 by means of a suitable bracket 44. The plunger 41 extends downwardly into contact with a cam member 45 which is pivotally mounted on a bracket 46 fixed to casing 43.

110 The timing mechanism for controlling the movements of cam member 45 is driven from a gear 47 on the main shaft 48 of the compressor through any suitable gear reduction mechanism including a gear 49. A shaft 50 is oscillated by the gear 49 through any suitable means such as a link 51 and a crank 52.

115 A pawl carrying member 53 is keyed to the shaft 50 and oscillated thereby. The pawl 54 is pivoted to the member 53 at 55 and engages teeth on a ratchet wheel 56. The ratchet wheel is thus intermittently rotated in one direction, being held against rotation in the opposite direction by a pawl 57 mounted on a stationary pivot 58. The ratchet wheel 56 is fixed to a hollow shaft 59 which surrounds shaft 50 and rotates in a bearing 60. Suitable means are provided for varying the number of teeth over which the pawl 54 may move at each oscillation of the pawl carrying 120 125 130

member. This means herein comprises a shield 61 which is fixed to an arm 62 rotatably mounted on the shaft 50. In order to adjust the position of this shield, a hand wheel 63 carries a nut which cooperates with a screw 64 to raise and lower a sliding block 65 which in turn is connected to the arm 62 by means of a link 66. The screw and sliding block are mounted in a suitable guiding member 67 mounted on the box-shaped member 43. On the end of the hollow shaft 59 is mounted a plate 68 which carries a fixed pin 69 projecting laterally therefrom and which has a series of holes 70 formed therein. It will be noted that these holes are arranged in a circle about the center of the plate and are adapted to receive a removable pin 71. It will be noted that the pin 69 is rotated so as to strike the arm 72 of the cam member 45 while pin 71 is positioned so as to strike the arm 73 of this cam member.

It is believed that the operation of my improved controlling mechanism will be readily understood in view of the above description.

Assuming first that the parts are in the position shown in Figs. 2, 3 and 6, with the three-way valve 23 in a position to admit pressure fluid from the receiver tank to the lower end of the cylinder 26, then the valve element 25 is held in its upper position allowing pressure fluid to pass through the notches 32 through pipe 20 to the unloader cylinder 14, thus holding the unloading mechanism in unloaded position. The valve 25 will remain in its upper position even though the pilot valve 16 operates to put pressure through line 19 since the area subjected to live pressure on the lower end of the valve is materially greater than the area subjected to pressure at the upper end of the valve. It will be noted that in Fig. 6 the pin 69 has just operated on the arm 72 to move the cam 45 into a position to elevate the plunger 41 and thus hold the valve elements 33 and 34 in their upper position as shown in Fig. 3. If it is desired to prevent the compressor from carrying more than a certain percentage of full load, the pin 71 will be displaced angularly counterclockwise relative to the pin 69 an amount corresponding to the percentage of desired unloading. As shown herein, the pin 71 is placed in the first hole or in position allowing the compressor to be loaded about ninety percent of the time. When the timing mechanism thus operates to elevate the plunger 41, the compressor is unloaded even if the pilot valve 16 is in loaded position. For example, if the pilot valve is in position to load the compressor, the line 19 will be vented to atmosphere and when the plunger 41 is elevated by the timing mechanism, pressure is admitted through line 22 and acts on the lower end of the valve, thereby elevating the same and admitting pressure to the unloader cylinder.

Operation of the compressor will actuate the timing mechanism through the reduction gearing 47, 49 and the plate 68 will be rotated in a clockwise direction by means of the ratchet and pawl mechanism 54, 56. The speed of rotation of this plate may be varied by changing the position of the shield 61 so that the pawl 54 may catch any number of teeth from one to seven or eight if desired. Upon rotation of the plate 68, the pin 71 engages arm 73 of the cam member and oscillates the cam to the position shown in Fig. 7, allowing the plunger 41 to drop. The lower end of the cylinder 26 is thus vented to the atmosphere through the line 22 and valve 23. The valve 25 therefore drops and permits the unloader pilot 16 to control loading and unloading in the usual manner during the period of operation between the time when pin 71 leaves the cam member and pin 69 again engages the cam member. If it is assumed that both the pilot valve 16 and the timing mechanism are in positions to put pressure on both sides of the three-way valve 21, the valve will be held in the position where it was at the time the condition was initiated due to the fact that one or the other of conical ends 27 or 28 will be covered by engagement with its respective seat, and hence there will be an unbalanced pressure force acting on the valve at the opened end thereof. It will thus be seen that the valve is prevented from being held in a position midway between its two extreme positions and will thus permit unloading of the compressor.

As a result of my invention it will be evident that means are provided for limiting the load which may be placed on the compressor. Also the interval during which it is desired that the average load shall be maintained at a minimum may be varied to suit different conditions by varying the speed of rotation of the plate 68. This is accomplished by adjusting the position of the shield 61 by means of hand wheel 63. Besides varying the length of the total interval, the proportion of unloaded to loaded operation may be varied by selecting the proper hole 70 to receive the removable pin 71. Also, if it is desired to permit the compressor to run loaded without interference from the timing mechanism, this may be accomplished either by removing the pin 71 or disengaging the pawl 54 from the ratchet wheel. The cost of power is thus kept at a minimum consistent with the average demand for air by adjusting the position of pin 71 to the proper percentage of full load. While this control mechanism will allow the compressor to run fully loaded for a short period of time, the average load over a period designated by the power company will be reduced to a minimum.

While I have in this application specifically described one form which my invention

may assume in practice, it will be understood that this form of the same is shown for purposes of illustration and that the invention may be modified and embodied in various 5 other forms without departing from its spirit or the scope of the appended claims.

What I claim as new and desire to secure by Letters Patent is:

1. In an automatic compressor control system, a compressor, an unloading device for unloading said compressor when subjected to pressure, a pilot valve for controlling said unloading device to load and unload the compressor in response to receiver tank pressure, 10 and means for preventing said pilot valve from relieving said device of pressure over a predetermined percentage of time.
2. In an automatic compressor control system, a compressor, an unloading device for unloading said compressor when subjected to pressure and for loading the same when relieved of pressure, a pilot valve for controlling pressure to said unloader to load and 20 unload the compressor in response to receiver tank pressure, a three-way valve in the line leading from the said pilot valve to said unloader, a second connection leading from said three-way valve to the receiver tank, and means for preventing said pilot valve from 25 relieving the pressure of said unloader at predetermined time intervals including means for conducting pressure fluid through said second connection and through a valve to said unloader.
3. In an automatic compressor control system, a compressor, an unloading device for unloading said compressor when subjected to pressure, a pilot valve for controlling pressure to said unloader to load and unload said 30 compressor in response to receiver tank pressure, a three-way valve in the line leading from said pilot valve to said unloader, a second connection leading from the three-way valve to the receiver tank, and means for preventing said pilot valve from relieving said unloader of pressure at intervals including 35 means for controlling said second connection for intermittently allowing pressure fluid to flow from said receiver tank through said three-way valve to the unloader, said controlling means including means for venting the unloader through said three-way valve, and means in said three-way valve for preventing communication between the unloader and that one of the other connections which is not subjected to pressure.
4. In an automatic compressor control system, the mechanism set forth in claim 3 including means provided by said three-way valve for holding the same in one of its extreme positions when both the connections from said pilot valve and the other connection from the receiver are subjected to pressure.
5. In combination, a power consuming de-

vice, means for limiting the maximum average power required by said device over a definite period of time to a predetermined percentage of full load, said means comprising mechanism to reduce the load for a predetermined period at definite regular time intervals, said mechanism being adjustable to vary the duration of said intervals while maintaining said periods uniform.

6. In combination, a power consuming device, means for limiting the maximum average power required by said device over a definite period of time to a predetermined percentage of full load, said means comprising mechanism to reduce the load after uniform periods of loaded operation, said mechanism being adjustable to vary the periods of reduced load while maintaining the periods of loaded operation of uniform length.

7. In combination, a power consuming device, means for limiting the maximum average power required by said device over a definite period of time to a predetermined percentage of full load, said means comprising mechanism to reduce the load for a predetermined time at definite regular time intervals, said mechanism being adjustable to vary the fraction of each interval when the mechanism is effective to reduce the load and also to vary the frequency of said intervals.

8. In an automatic compressor control system, a compressor, an unloading device for unloading said compressor when subjected to pressure, a pilot valve to supply pressure fluid to said unloader to unload the compressor in response to high compressor discharge pressure and to vent said unloader to cause loading of the compressor upon the occurrence of low compressor discharge pressure, and means operating at predetermined time intervals for supplying pressure to said unloading device and preventing the effective venting of the same by said pilot valve regardless of compressor discharge pressure.

9. In combination, a fluid compressor, and means for limiting the maximum average power required by said compressor over a definite period of time to a predetermined percentage of full load, said means comprising mechanism for effecting total unloading of the compressor, timing mechanism driven from said compressor, and means actuated by said timing mechanism to cause unloading for a predetermined time at definite regular time intervals, said timing mechanism being adjustable to vary the frequency of said intervals.

10. An automatic compressor control system comprising, in combination, a compressor, means for automatically loading and unloading said compressor in response to variations in compressor discharge pressure, automatic means for effecting unloading of said compressor independently of variations in compressor discharge pressure, and means

- associated with both of said automatic means for preventing under certain predetermined conditions effective operation of one of said automatic means.
5. 11. An automatic compressor control system comprising, in combination, a compressor, means for automatically loading and unloading said compressor in accordance with variations in compressor discharge pressure, and automatic means for effecting unloading of said compressor independently of variations in compressor discharge pressure including a vent and means for automatically variably controlling the same in accordance with desired operating conditions.
10. 12. An automatic compressor control system comprising, in combination, a compressor, fluid actuated means for automatically loading and unloading said compressor in accordance with variations in the compressor discharge pressure, and automatic means for effecting unloading of said compressor independently of variations in compressor discharge pressure and while the compressor runs at normal speed, including a vent for the fluid pressure which actuates said loading and unloading means, and means for controlling said vent automatically upon actuation of one of said automatic load controlling means.
15. 13. In combination, a power consuming device, means for limiting the maximum average power required by said device over a given period of time to a predetermined percentage of that at full load, said means including a fluid controlled mechanism for affecting the load on said power consuming device, and a fluid actuated control valve for controlling said load mechanism to effect said limited maximum average power.
20. 14. In combination, a power consuming device, means for limiting the maximum average power required by said device over a definite period of time to a predetermined percentage of that at full load, said means including a fluid controlled mechanism for effecting loading or unloading of said power consuming device, a fluid actuated control valve for controlling said loading and unloading mechanism, a vent for the actuating fluid of said controlled mechanism and control valve, and means adapted to variably control said vent automatically during operation of said loading and unloading mechanism.
25. 15. In combination, a power consuming device, means for limiting the maximum average power required by said device over a given period of time to a certain percentage of that at full load, said means comprising mechanism to reduce the load on said device, additional means for effecting reduction of the load on said device in accordance with certain operating conditions, a movable controlling member common to each of said load

reducing mechanisms and adapted to have a plurality of operating positions in either of which the controlling member is immovable, said common member being in one position to effect load reduction by one of said mechanisms and in another position to effect load reduction by the other of said mechanisms.

70. 16. In combination, a power consuming device, means for limiting the maximum average power required by said device over a given period of time to a certain percentage of that at full load, said means comprising mechanism to reduce the load on said device, additional means for effecting reduction of the load on said device in accordance with certain operating conditions, and a controlling member common to each of said load reducing mechanisms and adapted to be in one or the other of two positions in accordance with which load reducing mechanism is operative, connections for actuating said common member by one or the other of said load reduction mechanisms, and means whereby when the common member is in one position it is adapted to remain there irrespective of the operation of one of said load reduction mechanisms.

In testimony whereof I affix my signature.
JOHN W. SANFORD.
